(57) **CLAIM**

The ornamental design for a microphone stand, as shown and described.

DESCRIPTION

FIG. 1 is a top perspective view of a microphone stand showing our new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view taken from circle 9 in FIG. 1;

FIG. 10 is a partial enlarged view taken from circle 10 in FIG. 1; and,

FIG. 11 is a partial enlarged view taken from circle 11 in FIG. 7.

The dot dash broken lines encircling portions of the microphone stand in FIGS. 1 and 7 and illustrated in enlarged views of FIGS. 9, 10, and 11 form no part of the claimed design.

The dot-dash broken lines in the drawings are included for the purpose of depicting the partial enlarged views.
